INVENTOR

BY

D. C. Davis
ATTORNEY

UNITED STATES PATENT OFFICE.

JOHN H. SMITH, OF PHILADELPHIA, PENNSYLVANIA, ASSIGNOR TO WESTINGHOUSE ELECTRIC & MANUFACTURING COMPANY, A CORPORATION OF PENNSYLVANIA.

AIR EJECTOR.

Application filed February 1, 1922. Serial No. 533,288.

To all whom it may concern:

Be it known that I, JOHN H. SMITH, a citizen of the United States, and a resident of Philadelphia, in the county of Philadelphia and State of Pennsylvania, have invented a new and useful Improvement in Air Ejectors, of which the following is a specification.

My invention relates to ejection apparatus and more particularly to air ejection apparatus of the multistage, intercooler type, such as is used in power plant installations in connection with steam condensers, and it has for an object to provide apparatus of the character designated which shall be composed of standard units of different sizes, assembled to form a complete ejector organization of any desired capacity.

Another object of my invention is to provide an ejector organization assembled from units or elements having the same outside dimensions but of different ratings or capacities, which are interchangeable and which may be readily assembled, and in which certain portions of each unit may be isolated during operation for inspection or repair. These and other objects of my invention will appear more fully in the annexed specification, having reference to the accompanying drawing in which Fig. 1 is a longitudinal section through one element of an ejector organization constructed in accordance with my invention; Fig. 2 is a similar sectional view through a modified form of my device; Fig. 3 is a transverse section through a two-element organization, taken on the line I—I—III of Fig. 1; Fig. 4 is a view similar to Fig. 1, illustrating the application of the jet type of intercooler, and Fig. 5 is a view partially in elevation, and partially in section on the line V—V of Fig. 4.

My invention contemplates the provision of an air ejector organization assembled from unit elements, each element consisting generally of a first stage ejector 10, a second stage ejector 20, and an intercooler 15 located between the ejectors 10 and 20. The

ejector 10, which is of the well known steam jet type, consists of a nozzle 11 and a combining tube 12, and is adapted to exhaust air and other gases from a manifold 13 connected by a valve 14 to a condenser or other apparatus served. Similarly, the ejector 20 consists of a nozzle 21 and a combining tube 22 and is adapted to exhaust air and non-condensable vapors from the intercooler 15 in a manner well understood in the art to which my invention relates. The combining tube 12 is connected by a conduit 17 to an inlet 18 of the intercooler 15, by means of which the exhaust from the ejector 10 plus the motive steam from the nozzle 11 is introduced into the intercooler. The intercooler 15 consists of a shell 19 provided on its upper side with the inlet 18 and on its lower side with an outlet 23 and a drain 24, and is provided with tubes 26 through which cooling water is circulated to effect the condensation of steam and vapor in the shell 19. The condensate is removed through the drain 24, in any well known manner, to any desired point, assisted by baffles which tend to prevent the efflux of condensate through the outlet 23. Air and other non-condensable fluid are withdrawn from the intercooler through the outlet 23 by the ejector 20, which exhausts to a discharge manifold 27, in a manner readily understood. The manifold 27 may be provided with a non-return valve 28 if desired.

The intercooler shells are constructed in two or more sizes, corresponding to the capacities of the ejectors; an assembly of two sizes being shown in Fig. 3. The sections are similar in construction, having the same diameter and being provided at each end with the standard flanges 38; the distinction as to size being secured by difference in length. The outside ends of each of the two outside sections of the intercooler assembly carry a tube sheet 35, the diameters of which correspond to the diameter of the shells, and which are adapted to be clamped against the standard flanges 38. The tube sheets 35 are adapted to carry the tubes 26

which extend throughout the length of the assembled intercooler and by means of which cooling water is circulated.

One end of the assembly is provided with 5 a cap member 33 having flanges adapted to be bolted or otherwise secured to the standard flanges 38 and to clamp the tube sheet 35 in position. The cap member 33 together with the tube sheet 35 defines a reversing 10 chamber 37 by means of which counter-flow of the cooling water is effected. The other end of the assembly is provided with a header member 41, having an integral partition 40, by means of which the tube sheet 15 35 at that end is clamped in place, and which defines, with the tube sheet 35, a pair of chambers 42 to effect the feed of cooling water to the tubes 26. The header member 41 is provided with a cooling water inlet 20 43 and outlet 44 connected in a cooling water circulating system in any well known manner (not shown).

By means of the standard flanges 38, the 25 various sections of the apparatus are secured together in the usual manner by bolts (not shown). Each section is provided with the inlet 18 and the outlet 23, which inlets and outlets are of a uniform size and are provided with standard pipe flanges.

30 As members constituting an element of my ejector organization are constructed of a uniform size and are provided with standard flanges, any member from one element is freely interchangeable with a similar member from another element. In assembling 35 the complete elements of my organization to form ejection apparatus of any desired capacity, the elements are placed in position and the flanges 38 of the intercoolers bolted 40 or otherwise secured together in abutting relation. The tube sheets 35 and 39 are next installed, carrying between them tubes 26 of a proper length to extend through the several intercoolers of the assembled apparatus 45 in series. The header members 36 and 41, and the cap member 33 are then placed in position and the various steam or water connections made on each element, when the device is ready for use.

50 It will be apparent that by carrying in stock a comparatively few elements having ejectors of different capacities, the manufacturer is enabled to quickly and cheaply erect a complete ejection organization having any 55 desired commercial capacity. The flexibility of service made possible by my invention thus presents an enormous advantage over the systems now in vogue among manufacturers, which necessitates either the building 60 of individual apparatus to order for each installation, or the carrying in stock of a great variety of ejectors of different styles, designs and capacities.

The adaptability of my unit construction

may be illustrated in the following example, 65 using two sizes of units, A and B, having capacities represented by the arbitrarily selected values 1 and 3:

Elements in the organization.	Capacity of each element.	Total capacity of the organization.	70
A	1	1	
A+A	1+1	2	
B or	3 or		
A+A+A	1+1+1	3	
A+B	1+3	4	
A+A+B	1+1+3	5	
B+B	3+3	6	
A+B+B	1+3+3	7	

By these means of selection or combination, 80 an organization may be assembled upon receipt of the order by the manufacturer, to any desired capacity within the range of commercial demand.

In Fig. 2 I have illustrated a modification 85 of my invention in which I provide for the temporary isolation of either stage of the apparatus together with the intercooler. A by-pass 46 having a suitable valve 47, connects the manifold 13 with the inlet of the ejector 20, and the valves 48 and 49 are 90 located just before the ejector 10 and beyond the intercooler 28, respectively. By closing the valves 48 and 49 and opening the valve 47, the first stage ejector 10 and the intercooler 15 may be isolated for inspection or 95 repair, the apparatus then operating on the second stage ejector 20 through the by-pass 46.

A similar by-pass 51, having a valve 52, connects the exhaust end of the combining 100 tube 12 with the discharging manifold 27. A valve 53 is located between the combining tube 12 and the intercooler inlet 18, and a valve 54 is located between the combining tube 22 and the discharge manifold 27. By 105 closing valves 47, 53 and 54 and opening valves 48 and 52, the intercooler 15 and the second stage ejector 20 may be isolated for inspection or repair, the apparatus then operating on the first stage ejector 10 through the by-pass 51. By closing the valves 49 and 53, and opening all others, the intercooler 15 may be isolated, the ejectors 10 and 20 then operating in parallel. During normal operation 110 of the apparatus, the valves 47 and 52 are closed, and all the other valves open.

In Figs. 4 and 5 I have illustrated a modification 115 of my invention in which I provide intercooler elements of the jet type. The fluid exhausted from the primary ejector 10 passes through the conduit 17 to the inlet 18 of the intercooler 15, where it is subjected to the condensing action of water from the nozzles 59, mounted in the nozzle boxes 58. The nozzle boxes 58 are supplied with cooling water through the pipes 60 from a header 61, connected to any suitable source. The intercooler 15 is provided with the baffle 120

plates 56, forming a mixing chamber 57. The non-condensable fluids pass through the outlet 22 to the second stage ejector 20, while the condensate, plus the cooling water, passes out through the drain pipes 24 to a header 62, from which it is removed by any suitable means.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In a multistage air ejector organization, in combination, a plurality of elements, each element comprising a first stage ejector, a second stage ejector and an intercooler between said first and second stage ejectors, means connecting the elements to form the assembled ejector organization and means supplying cooling fluid to said intercoolers.

2. In a multistage air ejector organization, in combination, a plurality of elements, each element comprising a first stage ejector, a second stage ejector and an intercooler, flanged connections associating the elements to form the assembled ejector organization, and means common to all of said elements for supplying cooling fluid to said inter-coolers.

3. In a multistage air ejector organization, in combination, a plurality of elements of different capacities, each element comprising a first stage ejector, a second stage ejector and an intercooler between said first and second stage ejectors, means connecting the elements to form the assembled ejector organization, and means common to all of said elements for supplying cooling fluid to said intercoolers.

4. In a multistage air ejector organization, in combination, a plurality of elements of different sizes, each element comprising a first stage ejector, a second stage ejector and an intercooler, flanged connections associating the elements to form the assembled ejector organization, and means common to all of said elements for supplying cooling fluid to said intercoolers.

5. In a multistage air ejector organization, in combination, a plurality of elements of different sizes, each element comprising a first stage ejector, a second stage ejector and an intercooler, and means connecting the elements to form the assembled ejector organization, said means comprising standard flanges of uniform size whereby elements of different sizes may be assembled to form ejector organizations of different capacities.

6. In a multistage air ejector organization, in combination, a plurality of elements of different capacities, each element comprising a first stage ejector, a second stage ejector and an intercooler, means connecting the elements to form the assembled ejector organization, said means comprising standard flanges of uniform size whereby elements of different sizes may be assembled to form ejector organizations of different capacities, and means common to all of said elements for supplying cooling fluid to said intercoolers, said last named means including header sections for effecting reversal of the cooling fluid.

7. In a multistage air ejector organization, in combination, a plurality of elements having the same outside dimensions, each element comprising a first stage ejector, a second stage ejector and an intercooler, the ejectors in each element having different capacities; and means connecting the elements to form the assembled ejector organization.

8. In a multistage air ejector organization, in combination, a plurality of elements, having the same outside dimensions, each element including means connecting the elements to form the assembled ejector organization, said means comprising standard flanges of uniform size whereby elements of different sizes may be assembled to form ejector organizations of different capacities, each element comprising a first stage ejector, a second stage ejector and an intercooler, the ejectors in each element having different capacities; whereby an air ejector organization of any desired capacity may be built up of standard units.

9. In a multistage air ejector organization, in combination, a plurality of elements, each element comprising a first stage ejector, a second stage ejector and an intercooler, an inlet manifold connecting the first stage ejectors, a discharge manifold connecting the second stage ejectors, and a by-pass for each element from a point between the inlet manifold and the first stage ejector to a point between the intercooler and the second stage ejector.

10. In a multistage air ejector organization, in combination, a plurality of elements, each element comprising a first stage ejector, a second stage ejector and an intercooler, an inlet manifold connecting the first stage ejectors, a discharge manifold connecting the second stage ejectors and a by-pass for each element from a point between the first stage ejector and the intercooler to a point between the intercooler and the discharge manifold.

11. In a multistage air ejector organization, in combination, a plurality of elements, each element comprising a first stage ejector, a second stage ejector and an intercooler,

and means for isolating either ejector and the intercooler of each element.

12. In a multistage air ejector organization, in combination, a plurality of elements, each element comprising a first stage ejector, a second stage ejector and an intercooler, means for isolating the first stage ejector and the intercooler of each element, and means for isolating the intercooler and the second stage ejector of each element, said means comprising valved by-passes.

13. In a multistage air ejector organization, in combination, a plurality of elements, each element comprising a first stage ejector, a second stage ejector and an intercooler, and means comprising valved by-passes for isolating either ejector and the intercooler of each element, said by-passes having standard flanges of uniform size whereby they may be interchangeably fitted to elements of different sizes.

14. In a multistage air ejector organization, in combination, a plurality of elements of different sizes, each element comprising a first stage ejector, a second stage ejector and an intercooler between said first and second stage ejectors, means common to all of said elements for supplying cooling fluid to said intercoolers, header sections for effecting reversal of the cooling fluid, and means for isolating the first stage ejector and the intercooler of each element.

15. In a multistage air ejector organization, in combination, a plurality of elements of different sizes, each element comprising a first stage ejector, a second stage ejector and an intercooler between said first and second stage ejectors, means common to all of said elements for supplying cooling water to said intercoolers, header sections for effecting reversal of the cooling fluid, and means for isolating the intercooler and the second stage ejector of each element.

16. In a multistage air ejector organization, in combination, a plurality of elements of different sizes, each element comprising a first stage ejector, a second stage ejector and an intercooler, means for isolating either ejector and the intercooler of each element, means for interchangeably connecting the elements, and means for interchangeably connecting the isolating means to any of the elements.

17. In a multistage air ejector organization, in combination, a plurality of elements of different sizes, having the same outside dimensions, each element comprising a first stage ejector, a second stage ejector and an intercooler between said first and second stage ejectors, an inlet manifold connecting the first stage ejectors, a discharge manifold connecting the second stage ejectors, means common to all of said elements for supplying cooling fluid to said intercoolers, header sections for effecting reversal of the cooling fluid, means for isolating either ejector and the intercooler of each element, including valved by-passes, means for interchangeably connecting the isolating means to any of the elements, and means for interchangeably connecting the elements, comprising standard flanges of uniform size whereby elements of different sizes may be assembled to form ejector organization of different capacities.

18. In an ejector mechanism, in combination, a plurality of multiple stage ejector units, each unit comprising a plurality of stage ejectors connected in series and an intercooler interposed in the connection between the successive stage ejectors, and means for connecting the ejector units to form an assembled ejector mechanism.

19. In an ejector mechanism, in combination, a plurality of multiple stage ejector units of different capacities, each unit comprising a plurality of stage ejectors connected in series and an intercooler interposed in the connection between the successive stage ejectors, and means for connecting the ejector units to form an assembled ejector mechanism.

20. In an ejector mechanism, in combination, a plurality of multiple stage ejector units of different capacities, each unit comprising a plurality of stage ejectors connected in series and an intercooler interposed in the connection between the successive stage ejectors, and means for interchangeably connecting the units to form an assembled ejector mechanism.

In testimony whereof, I have hereunto subscribed my name this 27th day of January, 1922.

JOHN H. SMITH.
